WRIST COMPASS

Owsley H. Brigham, 7510 Morningside Drive,
Indianapolis, Ind. 46240

Filed Nov. 24, 1969, Ser. No. 20,231

Term of patent 14 years

Int. Cl. D10—07

U.S. Cl. D52—6

Fig. 1.

Fig. 2.

Fig. 3.

Fig. 4.

FIG. 1 is a top plan view of a wrist compass showing my new design;

FIG. 2 is a side elevational view;

FIG. 3 is an end elevational view; and

FIG. 4 is a bottom plan view.

In FIGS. 2-4 portions of the strap are omitted for convenience of illustration.

I claim:

The ornamental design for a wrist compass, as shown and described.
